Alex Conklin

United States Patent Office.

ALEXANDER CONKLIN, OF HARTFORD, CONNECTICUT.

Letters Patent No. 75,628, dated March 17, 1868.

IMPROVED REAMING-TOOL.

The Schedule referred to in these Letters Patent and making part of the same.

TO ALL WHOM IT MAY CONCERN:

Be it known that I, ALEXANDER CONKLIN, of Hartford, in the county of Hartford, and State of Connecticut, have invented a new and useful Expanding Reamer; and I do hereby declare that the following is a full, clear, and exact description of the construction and operation thereof, reference being had to the accompanying drawings, and to the letters of reference marked thereon.

Figure 1 shows a vertical section through the middle of the reamer.

Figure 2 shows an end view of the reamer.

Figure 3 shows a section on the line *x y*.

Like letters, in the figures, indicate like parts.

My invention consists in expanding or pressing out the cutting-teeth or leaves of the reamer, by means of a tapering plug, set so that by forcing it in by a screw, it presses out the teeth, so as to ream a larger hole; and also in securing the teeth in the desired position, by means of a nut pressing against their ends.

A is the stock or frame of the reamer, which is bored out to receive the plug *B*, and has slots cut in it for the teeth *C C*. The conical plug *B* is fitted with a screw-thread, *r s*, near its head, into the frame or stock *A*, for the purpose of moving it in or out, and at the other end it slides in the socket *E*, to hold and guide it. The screw can also be cut in this socket, instead of near the head. This plug has a slot in its head, or other suitable contrivance, for turning it. The cutting-teeth or leaves, *C C*, are fitted into slots in the frame or stock *A*, passing through into the interior cavity, and resting upon the inclined surface *m n* of the conical plug *B*, the inside edges of the teeth being made at such an inclination as to rest upon the plug *B* when the cutting-edges are in the proper position. The clamping-nut *D* screws on to the end of the frame or stock *A*, which is cut down smaller to receive it, leaving a shoulder against the face of the nut. The ends of the teeth *C C* project slightly beyond this shoulder, so that the face of the nut *D* presses upon them when screwed up, and holds them firmly in their places. The nut *D* has two of its sides flattened, as shown in the drawings, or some other suitable common device, for turning it up with a wrench.

The operation of my invention is as follows: When it is desired to enlarge the reamer, the clamping-nut *D* is loosened, and the conical plug *B* is screwed farther in. The bottom edges of the teeth *C C* slide up farther on the conical part of the plug *B*, which presses them out. The clamping-nut *D* is then screwed up tight against the ends of the teeth, and holds them firmly in their new position. When it is desired to reduce the size of the reamer, the nut *D* is loosened, and the plug *B* screwed out the desired distance. The teeth are then pushed in against it, and the nut *D* tightened as before.

My invention can also be used as an expanding tap for cutting screw-threads, by giving the outer edges of the leaves or teeth the proper form. It can also be used as an expanding arbor or mandrel, in which case the leaves or teeth would be without cutting-edges.

Claim.

What I claim as my invention, and desire to secure by Letters Patent, is—

The combination of the devices *A B C D*, constructed and operating substantially as described, when used to form an expanding tool as herein specified.

ALEX. CONKLIN.
